OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

TALLY-ROLL ATTACHMENT FOR TYPE-WRITING MACHINES.

1,029,153.

Specification of Letters Patent. Patented June 11, 1912.

Application filed September 23, 1910. Serial No. 583,438.

To all whom it may concern:

Be it known that I, OTTO THIEME, a citizen of the United States, residing at St. Louis, Missouri, have invented a certain new and useful Improvement in Tally-Roll Attachments for Type-Writing Machines, of which the following is a full, clear, and exact description, such as will enable others skilled in the art to which it appertains to make and use the same, reference being had to the accompanying drawings, forming part of this specification, in which—

Figure 1 is a front elevational view of my device as applied to an ordinary typewriter. Figs. 1^a and 1^b are modified views of the operating levers. Fig. 2 is a side elevation. Figs. 3, 4, 5 and 6 illustrate details of construction.

My invention relates to an improvement in adjustable tally roll attachment for typewriting machines. It is of advantage in a mercantile establishment to make out a tally roll or sheet simultaneously with the ledger sheet for a day's work or longer.

It is my object to provide a very simple attachment to be applied to any ordinary form of typewriter, which attachment would properly feed such a roll to the platen of the typewriting machine.

Referring to the drawings 1 indicates generally the typewriting machine with an ordinary carriage 2 and platen 3. Across the back of the carriage is mounted an ordinary rack bar 4, and in the front of the carriage is a square or rectangular supporting bar 5. These bars 4 and 5 extend across the carriage and are properly supported thereon.

Slidably mounted on the bar 4 is a bracket 6 having an angular extension 7 carrying a roll support 8 with notches 9 at the top for the reception of a rod 10 upon which the paper roll 11 is mounted. The rod 10 is comprised of a center portion having grooves 10' thereon at intervals near either end and is internally bored at either end as designated at 12. Within either bore is slidably mounted a pin 13 grooved at 14 and with a knurl head 15.

In the bottom of the bore 12 and bearing against the end of the pin 13 is a suitable spring 16. The grooves 10' are provided to form a stop for collars 17 having spring actuated pawls 17' adapted to engage therein, mounted on either side of the roll 11 and

the spring pins 13 provide an adjustable bearing to be held in position in the support 8, the springs allowing of the extension and retraction of the ends of the rod 10 according to the width of the support 8.

Suitably connected to the support 8, and the bracket 6 is a curved guard member 18, which is shaped to protect the tally sheet being unrolled from the roll 11, and passing over the members 7 and 6. As shown in Fig. 1 this guard member is slotted out to form three wings 19, 20 and 21, and a turn down part 22.

Pivoted to the bracket 6 is a catch device 23 having a toothed portion 24 adapted to engage between the teeth of the rack 4. A spring 25 normally holds the teeth 24 in engagement with the rack. A handle 26 is attached to the outside of the pivot pin 27 of the catch 23 so that it may be easily turned.

Slidably mounted on the bar 5 is a bracket 28 forming a support for the feeding roll 29 rotatably mounted on a spindle 30 journaled on the bracket. A suitable ratchet wheel 31 is also fast on the spindle 30 at one end, and a pawl carrying arm 32 is loosely mounted on this spindle adjacent the ratchet wheel. This arm carries a pawl 33 held in engagement with the ratchet by means of a spring 34. The arm 32 is also provided with a projecting portion 35 connected to a pin 36 on a slide bar 37 by means of a spring 38. This bar 37 is grooved at 39 to move upon the frame of the machine guided by a stud 40, and has an inclined toothed portion 41 adapted to engage the portion 35 of the arm 32 to move this arm in opposition to the action of the spring 38.

A leaf spring 42 is connected to the bracket 28 to bear against the end of the feeding roll 29 preventing excessive rotation thereof. The slide bar 37 is connected to a lever 43 pivoted on the same pivot 44 as is the lever 45, which actuates the ratchet wheel 46 on the platen 3. Each of these levers is provided with a projecting finger portion so that they may be independently operated if desired. The lever 43 is notched at 47 for the reception of a pin 48 attached to the lever 45. In the view shown in Fig. 1 the notch and pin are on the right hand edge of the levers, and in the view shown in Fig. 1^a, the notch and pin are on the left hand of the same levers.

The bracket 28 is slidably mounted on the bar 5 by being shaped to engage at least two sides thereof, and being held in engagement therewith by means of an adjustable screw 49. Suitable paper guide fingers 50 and guiding devices 51 are applied to the machine for the protection of the sheets fed to the platen.

The paper roll 11 as illustrated in Fig. 1 is formed of strips of different color 52 and 53 as, for example, pink and yellow, so that the credits may be listed on the pink sheet and the debits on the yellow sheet. When the device is in use the ledger sheet is introduced in the ordinary manner under the paper fingers 50 and around the platen with the carbon sheet between it and the tally sheet from the roll 11, the guard devices preventing the sheets from becoming soiled. 20 in passing to the platen. The tally roll attachment is adjusted so that the credit or debit sheet, as desired, is in register with the proper column on the ledger sheet, and the figures properly entered on both sheets simultaneously, then the attachment is readjusted and another set of figures introduced on whichever side of the tally sheet it is desired and in the proper column on the ledger sheet. By this means the credits for 30 the day and the debits may be entered on the tally sheet and at the same time on the book-keeping sheet or ledger.

The platen is fed in the usual manner by means of the lever 45 and the feeding roll 29 by means of the lever 43 through connection with the sliding rod 37 acting on the tail 35 of the pawl carrying arm 32. Provision is made in the link 37 for adjustment of the tally roll laterally of the carriage by a slot and screw construction, by which the length of the link may be changed as desired.

When the lever 43 is operated in the construction shown in Fig. 1 it also operates 45 the lever 45 through the pin and slot connection 47 and 48, so that with the parts as thus constructed the platen can be operated independently of the feeding roll 29, and the platen and feed roll be operated simultaneously.

In the construction shown in Fig. 1^a the lever 43 may be operated independently of the lever 45 to rotate the feed roll, but when the lever 45 is operated it also simultaneously operates the lever 43 and, therefore, both the feed roll and platen are rotated together. If desired the pin 48 could be made removable and the lever 43 provided with two slots as shown in Figs. 1 and 1^a, so that 60 either of these operations could be produced on the same machine, or the pin could be removed and both levers operated independently of each other.

I am aware that minor changes may be 65 made in the construction, arrangement and

combination of parts as illustrated and described without departing from the spirit of my invention, the scope of which is indicated in the accompanying claims.

I claim:

1. A tally roll attachment comprising a roll support and roll feeding means, a typewriter machine carriage having a rack bar, and an additional bar mounted thereon, means on the roll support for engaging the rack bar, and means on the feeding device for engaging the additional bar, both of said latter means permitting lateral adjustment of the tally roll support and feeding means.

2. A tally roll feeding means comprising a feeding roll with ratchet attached, a bracket forming a support for the roll adapted to be laterally adjustable on a bar, a ratchet pawl carrying arm adapted to actuate the ratchet having a projecting portion, a slide bar adapted to engage with said projecting portion of the arm to operate the pawl.

3. In a device of the character described, a typewriter carriage provided with a platen, a feed roll, a tally roll mounted behind the platen, a feeding device for the roll mounted in front of the platen, a guard member positioned in front of and adjacent the tally sheet as it passes from the roll, and a guide member directing the tally sheet behind the feed roll and under the platen.

4. In a longitudinally adjustable tally strip device a tally roll feeding means, comprising a feeding roll with ratchet attached, a bracket forming a support for the roll, a ratchet pawl-carrying arm adapted to actuate the ratchet, having a projecting portion, a slide bar adapted to engage the said projecting portion of the arm to operate the pawl, and a pivoted handle for operating the bar.

5. In a longitudinally adjustable tallying device a tally roll feeding means, comprising a feeding roll with ratchet attached, a bracket forming a support for the roll, a ratchet pawl-carrying arm adapted to actuate the ratchet, having a projecting portion, a slide bar having an inclined surface engaging the said projecting portion of the arm to operate the pawl, and a handle for operating the bar.

6. In an adjustable tally strip device a tally roll feeding means, comprising a feeding roll with ratchet attached, a bracket forming a support for the roll, a ratchet pawl-carrying arm adapted to actuate the ratchet, a slide bar adapted to engage a projecting portion of the arm to operate the pawl, and an operative handle connected with the slide bar.

7. In a typewriting machine, a traveling carriage having a rotating platen thereon, a tally roll device attached to the carriage

comprising a feeding means, a lever for rotating the platen, and a second lever for rotating the feeding means, said levers being located in proximity whereby they may be 5 simultaneously operated.

8. In a typewriting machine, a traveling carriage having a rotating platen thereon, a tally roll device attached to the carriage comprising a feeding means, a lever for rotating the platen, a lever for operating the feeding means, a pin attached to one lever operating in a slot in the other of the levers, whereby a movement of one lever will actuate the other.

15. 9. In a typewriting machine a traveling carriage having a rotating platen, a tally roll device attached to the carriage comprising a feeding means, a lever for rotating the

platen, and a lever for rotating the tally roll device and a machine pivot for the two 20 levers.

10. In a typewriting machine a traveling carriage having a rotating platen, a tally roll device attached to the carriage comprising a feeding means, a lever for rotating the 25 platen and a lever for rotating the feeding means, and connections between said levers, so that the operation of one will actuate the other.

In testimony whereof I hereunto affix my 30 signature in the presence of two witnesses this 12th day of September, 1910.

OTTO THIEME.
